I. B. ULLOM

ATTACHMENT FOR HOT AIR REGISTERS

Filed April 1, 1924

UNITED STATES PATENT OFFICE.

ISAAC B. ULLOM, OF WASHINGTON, PENNSYLVANIA.

ATTACHMENT FOR HOT-AIR REGISTERS.

Application filed April 1, 1924. Serial No. 703,566.

To all whom it may concern:

Be it known that I, ISAAC B. ULLOM, a citizen of the United States of America, and a resident of Washington, in the county of Washington and State of Pennsylvania, have invented a new and Improved Attachment for Hot-Air Registers, of which the following is a description.

My invention relates to an attachment 10 to be applied to a hot-air register in a manner to afford support for a dust-collecting curtain to prevent smoke and dust from marring walls adjacent to the register.

The general object of my invention is to 15 provide a curtain-supporting attachment and a detachable curtain therefor, the attachment to be so formed as to be readily applied to the hot-air register to exclude dust in the joint between the register and 20 the supporting wall.

A more specific object of the invention is to provide an attachment for the indicated purpose reflecting practical considerations with respect to simplicity and facility with 25 which the attachment may be emplaced.

The nature of the invention and its distinguishing features and advantages will clearly appear as the description proceeds.

Reference is to be had to the accompanying 30 drawings forming a part of this specification, it being understood that the drawings are merely illustrative of one example of the invention.

Figure 1 is a perspective view of a curtain and a curtain-support embodying my 35 invention;

Figure 2 is a view similar to Figure 1 but with the curtain omitted;

Figure 3 is a transverse vertical section 40 with the curtain and curtain support in a plane indicated by the line 3-3, Figure 1;

Figure 4 is a fragmentary front elevation of the curtain and support as applied to the 45 register;

Figure 5 is a detail in cross section on the line 5-5, Figure 4.

In carrying out my invention in accordance with the illustrated example, a frame 10 is provided, presenting legs or standards and a top cross bar uniting the standards. The standards or legs, as well as the top cross bar of the frame have applied thereto a metal covering 11 terminating in

parallel flanges 12 between which is held a strip 13 of felt, asbestos, or like material. 55

At the top of the frame the covering 11 has transverse cut-outs 14 which receive tongues 15 on a curtain-holding strip 16, said tongues being bent about the frame 10 at said cut-outs 14. The strip 16 at the 60 outer free edge thereof has rearwardly directed teeth 17 to engage the curtain.

A bracket 18 is employed generally of inverted U-shape and presents oblique members, the lower ends of which terminate in 65 vertical members received in sockets 20 formed on clips 19 applied to the standards of the frame 10 as clearly shown in Figure 1. The top cross bar 21 of the bracket 18 has applied thereto a clip or covering strip 70 22 of sheet metal which is formed with a toothed flange 23 directed forwardly for engaging a curtain.

A curtain 24 is formed with a front, sides, and a top, the bottom and rear of the curtain being open. The rear edge of the top of the curtain 24 is engaged with the teeth 17 as shown in Figure 3, while the teeth 23 engage the curtain at the angle formed by the front and top of the curtain. 75 80

The curtain-holding frame and its appurtenances are emplaced behind a register A by removing the usual screws C which are generally employed to affix a register to the wall B. The frame 10 with its covering 11 is then positioned against the wall at the back of the register A so that the strip 13 forms a closure at the top and sides of the wall opening D. The bracket 18 supports the curtain at the front while the strip 16 supports the curtain at the back. Said curtain 24 prevents the rising of dust within the room and the strip 13 prevents dust entering at the top and sides between the register A and the wall B. Thus, the wall is 85 90 95 protected from becoming soiled or discolored by any smoke or dust escaping through the register A.

I would state in conclusion that while the illustrated example constitutes a practical embodiment of my invention, I do not limit myself strictly to the exact details herein illustrated, since, manifestly, the same can be considerably varied without departure from the spirit of the invention as defined 100 in the appended claim. 105

Having thus described my invention, I claim:

An attachment for hot-air registers including a frame having spaced sides and a top cross bar in approximately the plane of the sides and adapted to be emplaced at the back of a hot-air register, sheet metal

covering on said frame at the sides and top, said covering at the top of the frame having rearwardly directed curtain-engaging teeth, and additional curtain-supporting means on said frame forward of said top bar and its curtain-supporting teeth. ¹⁰

ISAAC B. ULLOM.
